UNITED STATES PATENT OFFICE.

LARS ANDREW LARSEN, OF BOSTON, MASSACHUSETTS, ASSIGNOR TO CARR
FASTENER COMPANY, OF CAMBRIDGE, MASSACHUSETTS, A CORPORATION
OF MAINE.

SEPARABLE FASTENER.

1,387,105.

Specification of Letters Patent.

Patented Aug. 9, 1921.

Application filed January 16, 1920. Serial No. 351,771.

To all whom it may concern:

Be it known that I, LARS ANDREW LARSEN, a subject of the King of Norway, and a resident of Mattapan District, city of Boston, in the county of Suffolk and State of Massachusetts, have invented an Improvement in Separable Fasteners, of which the following description, in connection with the accompanying drawings, is a specification, 10 like characters on the drawings representing like parts.

This invention pertains to improvements in separable fasteners and more particularly, though not exclusively, to improvements in 15 separable fasteners of the three-side lock type, in which stud and socket are locked against separating movement produced by a force-producing relative tipping movement in three directions, while permitting separation of stud and socket by a force-producing tipping movement in a fourth direction.

In the drawings, which show a preferred embodiment of one form of my invention:—

25 Figure 1 is a front elevation of a separable fastener;

Fig. 2 is a section, partly in elevation, on the line 2—2 of Fig. 1;

Fig. 3 is a rear elevation of the socket; 30 and

Fig. 4 is a front elevation of the stud shown in the other figures.

As shown in the accompanying drawings, the preferred form of my invention includes 35 a stud having a head 5, and a neck 6, preferably provided with a shank portion 7, and a base portion 8. The preferred form of stud is resilient, being provided with a plurality of slots, herein shown as four in number, and preferably being formed by two intersecting cuts 9, which preferably not only extend the entire length of the stud, but preferably extend somewhat into the base 8 so that an opportunity is afforded for resiliency arising primarily in the base of the 45 stud along lines between the ends of the adjacent cuts.

The stud described in the preceding paragraph preferably coöperates with a socket 50 providing a stud-receiving aperture adapted to engage the neck 6 of the stud and of such effective size that the head 5 of the stud can pass therethrough when compressed.

The shoulder between the head 5 of the 55 stud and the neck 6 preferably slopes some-

what so that when the stud and socket are tipped, one relative to the other, the head will be compressed and separation of stud and socket easily effected.

Tipping movement is preferably precluded 60 in all directions except one, viz., that direction produced by a pull on the bottom of the socket shown by an arrow in Fig. 2 of the drawings. This may conveniently be effected by providing an elongated opening adapted 65 to engage the shank of the stud on three sides, to prevent substantial tipping, while I leave sufficient clearance on the fourth side to permit any desired amount of tipping.

In the preferred construction shown in 70 the drawings, I have provided an aperture, the sides of which are adapted to engage the neck 6 in a jaw plate 10, and I have limited the directions of tipping movement by a shank-engaging plate 11 having an elongated 75 aperture therein which may be provided with a curb to increase the amount of bearing surface.

The plates 10 and 11 may conveniently be secured to a curtain 12 by a fastening plate 80 13 located on the opposite sides of the curtain and having prongs 14 adapted to project through the curtain, and preferably through the plates 10 and 11, and to be clenched thereon as best shown in Fig. 3. 85

While I have shown and described a preferred form of one embodiment of my invention, it will be understood that changes involving omission, substitution, alteration and reversal of parts, and even changes in 90 the mode of operation, may be made without departing from the scope of my invention, which is best defined in the following claims.

Claims:

1. A stud for separable fasteners including a head, a neck, a shank portion and a base portion, the combined length of said head, neck and shank portions being substantially greater than the diameter of any of them, said head portion, said neck portion, said shank portion and a part of said base portion being slotted to provide a resilient stud having the resiliency initiating in the base portion. 95

2. A stud for separable fasteners having 105 a head, a neck, a shank and a base, the combined length of said head, neck and shank portions being substantially greater than the diameter of any of them, said head, neck and shank being divided throughout their 110

entire length by a slot terminating in said base portion.

3. A stud for separable fasteners having a head, a neck, a shank and a base, the combined length of said head, neck and shank portions being substantially greater than the diameter of any of them, said head, neck and shank being divided throughout their entire length by a plurality of slots terminating in said base portion.

4. A stud for separable fasteners having a head, a neck, a shank and a base, the combined length of said head, neck and shank portions being substantially greater than the diameter of any of them, said head, neck and shank being divided throughout their entire length by two slots at right angles to one another and terminating in said base portion.

5. A stud for separable fasteners having a head, a shank and a neck, the combined length of said head, neck and shank portions being substantially greater than the diameter of any of them, said stud slotted in planes extending longitudinally thereof and, except for the slots, said stud being symmetrical in cross-section.

6. A separable fastener comprising, in combination, a resilient stud having a head and a neck, said stud slotted to provide resiliency, and round in cross-section, and a socket providing an aperture therein adapted to permit passage of the head of said stud when compressed, the margins of which are adapted to engage said neck when in juxtaposition thereto, said socket including limiting means opposing relative tipping movement of said stud and socket in one direction, while permitting such relative tipping movement in another direction.

40 7. A separable fastener comprising, in combination, a resilient stud having a head and a neck, said stud slotted to provide resiliency, and round in cross-section, and a socket providing an aperture therein adapted to permit passage of the head of said

stud when compressed, the margins of which

are adapted to engage said neck when in juxtaposition thereto, said socket including limiting means opposing relative tipping movement of said stud and socket in three directions, while permitting such relative tipping movement in a fourth direction only.

8. A separable fastener comprising, in combination, a stud and socket, said stud slotted longitudinally to provide resiliency and adapted to function without change irrespective of turning thereof about its longitudinal axis relatively to said socket, and said socket providing stud-engaging jaw means and means on the socket for limiting the directions in which said stud and socket may be tipped one relative to the other.

9. A separable fastener comprising, in combination, a stud having a head and a neck; and a socket; said stud and socket separable by relative tilting movement in one direction only; said socket providing a stud-receiving orifice having unyielding jaw means on opposite sides thereof for engagement with the neck of the stud; said stud being generally symmetrical in cross-section, being resilient, and being adapted to have its head enter the orifice in the socket in any relative radial position, thereby to provide a three-side lock fastener having the resiliency in the stud and in which no determined radial registration of the stud with the socket is necessary.

10. A separable fastener comprising, in combination, a stud generally round in cross-section and providing a head and a neck, said stud slotted longitudinally to provide resiliency, and a socket providing a portion closely fitting said neck of said stud, and a second portion, rearwardly of the first-mentioned portion, for limiting the direction of possible relative tipping movement between stud and socket.

In testimony whereof I have signed my name to this specification.

LARS ANDREW LARSEN
